COLLAPSIBLE REEL

Freeman H. Owens, New York, N. Y.

Application April 23, 1929, Serial No. 357,592
Renewed September 12, 1933

3 Claims. (Cl. 242—72)

This invention relates to improvements in a collapsible film reel, and more particularly to such reels as are used as hubs or cores upon which film is wound, the principal object of the invention being to provide improved means for changing the diameter of the reel so as to facilitate the removal of the film therefrom.

Other objects and advantages of the invention will appear as the description proceeds.

10 In the drawing accompanying this specification, Figure 1 is a front elevation of a pulley embodying the features of the present invention.

Figure 2 is a sectional side view taken approximately on the line 2—2 of Figure 1.

15 Figure 3 is a transverse sectional view taken approximately on line 3—3 of Figure 2.

Figure 4 is a side view of the reel in collapsed position.

20 The same characters of reference designate the same parts in the different figures of the drawing.

Referring to the drawing, 1 and 2 designate a pair of semicircular segments which are preferably identical in construction so as to be interchangeable. Each of said segments comprises a hub-forming portion 1a and 2a respectively, a circumferential flange portion 1b and 2b, and a pair of radially extending web portions 1c, 2c connecting the hub and circumferential flange portions.

30 The segments are secured together with their webs 1c and 2c normally spaced a small distance apart as shown in Figure 2, and in order to maintain them rigidly in that position I have provided 35 each of the webs 1c, 2c with a pair of perforations so located that when the segments are assembled in operative position the perforations in the webs of one segment will register with the corresponding perforations of the other segment. Through 40 the outermost perforations in each pair of webs 1c, 2c extends a pin 3, having a head 4 at each end thereof, said heads being secured to said pin 3 as by the locking keys 4a.

45 Each of the pins 3 is prevented from turning in its opening by means of a pin or key 7 driven through the webs in intersecting relation to the pin 3 so as to engage a notch or dent 8 formed in said pin. The remaining perforations in the webs 1c, 2c are formed in one of each pair of webs 50 to provide a seat for a shouldered pin 9 having an elongated extension which projects through the corresponding perforation in the web of the opposed segment. The length of the pins 3 and 9 is such when the webs of the segments are separated 55 a predetermined distance the end faces of

the elongated portions of pins 9 are flush with those surfaces of the opposed webs which are nearest the circumferential flange portions of the segments. In order to retain the segments in their spaced apart relation, a lever 10 is mounted 60 for rotation on each of the pins 3 between the web and the head 4, the lever being adapted to be swung or pivoted on the pin 3, so that when the segments are separated, the portions of the levers which lie parallel with the web can be carried into 65 position to overlie the perforations in which are located the extensions of pins 9, thereby closing the end of said perforations and preventing the ends of pins 9 from projecting beyond the surface of the webs, as shown in full lines in Figure 2 and 70 in dotted lines in Figure 3. The pins 3 and 9 are of such relative lengths that with the levers in this position pressure is exerted by the levers on the ends of pins 9, which, by means of its shoulders, forces and holds the webs of the segments 75 apart. The edges of the lever 10 are bevelled as at 10a whereby upon swinging the levers into engagement with the projecting ends of the pins 9, the tendency will be to force the pins and the segments in which they are mounted, away from the 80 lever and thus space the segments, as shown in Figure 1. This provides a simple and effective means for quickly spacing the segments when it is desired to wind film thereon.

It will be noted also that the pins 9 provide 85 guides for the segments whereby they are maintained in aligned position.

Obviously, after the film has been exposed and it is desired to remove it from the core for processing in the developing tank or for any other 90 purpose, it is necessary merely to swing the levers 10 out of contact with the ends of pins 9 and into the position shown in full lines in Figure 3, whereupon the webs of the opposed segments can readily be pressed together, thus reducing the 95 diameter of the reel in one direction so that the film can readily be removed therefrom. The flange portions are preferably split transversely as indicated at 12 to permit the insertion of an end of the film, whereby the same may be secured 100 against slipping, and the hub portion of one of the segments is provided with a radially extending set screw 13 for securing the reel for rotation with a shaft or spindle.

I claim:

1. A collapsible reel, comprising a pair of separable semicircular segments each having an integral diametrically extending web, means passing through the webs of both segments for securing them together but permitting a limited 110

separative movement, and releasable means for rigidly retaining the webs in parallel relation to the limit of their separative movement.

2. A collapsible reel, comprising a pair of separable semicircular segments each having a diametrically extending web, means passing through the webs of both segments for securing them together but permitting a limited separative movement, a projecting member carried by each of said webs and normally passing through the opposing web when the webs are in abutting relation, and releasable means for exerting pressure on said members when the webs are at the limit of their separative movement thereby rigidly retaining them in spaced relation.

15 3. A collapsible reel, comprising a pair of

separable semicircular segments each having a diametrically extending web, a headed pin secured in each of said webs and movable in the opposed web, said pins being of such length as to permit a limited separative movement of the webs and having means for preventing complete separation thereof, a pin seated in each of said webs and having an extension normally projecting through an opening in the opposed web, and pivoted members adapted to close said openings when the webs are at the limit of their separative movement thereby to prevent the passage of said pins and retaining the webs rigidly in parallel spaced relation.
